CLAIM

The ornamental design for an athletic shirt, as shown and described.

DESCRIPTION

FIG. 1 is a perspective view of the athletic shirt;

FIG. 2 is a front view thereof;

FIG. 3 is a back view thereof;

FIG. 4 is a top view thereof;

FIG. 5 is a bottom view thereof;

FIG. 6 is a right view thereof; and

FIG. 7 is a left view thereof.

The broken lines shown in the drawings are for the purpose of illustrating portions of the article and form no part of the claimed design.

1 Claim, 7 Drawing Sheets
